[57] CLAIM

I claim the ornamental design for a faucet handle, as shown.

DESCRIPTION

FIG. 1 is a left side elevation of a first embodiment of a faucet handle showing my new design, the opposite side being a mirror image thereof.

FIG. 2 is a front view thereof.

FIG. 3 is a rear view thereof.

FIG. 4 is a top view thereof.

FIG. 5 is a bottom view thereof.

FIG. 6 is a perspective view thereof.

FIG. 7 is a left side elevation of a second embodiment of a faucet handle showing my new design, the opposite side being a mirror image thereof.

FIG. 8 is a front view thereof.

FIG. 9 is a rear view thereof.

FIG. 10 is a top view thereof.

FIG. 11 is a bottom view thereof.

FIG. 12 is a perspective view thereof.

FIG. 13 is a left side elevation of a third embodiment of a faucet handle showing my new design, the opposite side being a mirror image thereof.

FIG. 14 is a front view thereof.

FIG. 15 is a rear view thereof.

FIG. 16 is a top view thereof.

FIG. 17 is a bottom view thereof; and,

FIG. 18 is a perspective view thereof.
